UNITED STATES PATENT OFFICE.

THOMAS CONNELL, OF IOWA CITY, IOWA.

DAMPER-REGULATOR.

1,302,635.

Specification of Letters Patent.

Patented May 6, 1919.

Application filed November 30, 1917. Serial No. 204,790.

To all whom it may concern:

Be it known that I, THOMAS CONNELL, a citizen of the United States, and resident of Iowa City, in the county of Johnson and State of Iowa, have invented a certain new and useful Damper-Regulator, of which the following is a specification.

The object of my invention is to provide a device adapted to be connected with a steam heating plant for automatically regulating the check and draft doors of a furnace.

More particularly it is my object to provide a device of the type using a water receptacle adapted to be filled with water according to the pressure in the boiler and to be automatically connected with the check and draft doors or both.

Still a further object is to provide such a device in which the movable receptacle is operatively connected with a return water chamber so that in case there should be any defect or check in the return system, whereby the system should be made ineffective on account of the failure of any proper return of the water, water will be supplied to the movable receptacle for thereby operating said receptacle.

Still a further object is to provide such a device adapted to automatically close an air vent in the system when the receptacle is moved to certain positions.

Still a further object is to provide such a device having a receptacle of the kind mentioned and having an air vent which device has means for automatically closing the last mentioned air vent when the receptacle is lowered.

I have thus provided in general a combined water receiver, and air separator and damper regulator controlled by boiler pressure or return water.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a front elevation of a furnace and part of a steam heating system and damper embodying my invention.

Fig. 2 shows a front elevation of the damper regulator attachment. 55

Fig. 3 shows a side elevation of the device shown in Fig. 2, parts being broken away and parts being shown in section.

Fig. 4 shows a vertical, sectional view through the top of the tiltable water receptacle, illustrating part of the mechanism for closing the vent therein. 60

Fig. 5 shows a top view of the device.

In the accompanying drawings, I have used the reference numeral 10 to indicate generally a furnace having a heating boiler 11. The furnace has a draft door 12 pivoted at its upper end, and a check draft door 13 also pivoted at its upper end. 65

Mounted on a suitable support 14 is a receptacle 15 which may have the form of a cylinder. A pipe 16^a communicates with the upper portion of the boiler and extends to a position above the receptacle 15 and thence downwardly to the upper interior of the receptacle 15. Adjacent to the receptacle 15 is a second receptacle 16, the lower interior of which communicates with the lower interior of the receptacle 15 by means of a tube 17. 70

In the side of the receptacle 15 is a glass 18 and suitable indicating characters 19 to show for instance the weight of water in ounces in the receptacle 15. 75

Rotatably mounted in the wall of the receptacle 16 by means of any suitable joint is a tube 20. Connected with the tube 20 outside the receptacle 16 is a tube 21, the free end of which supports and communicates with the lower portion of a tiltable water receptacle 22. Extending away from the other end of the tube 21 is a rod 23 on the end of which is an adjustable weight 24. 80

Below the tube 20 a plate 25 is centrally pivoted on the wall of the receptacle 16. 95 The ends of the plate 25 are provided with curved slots 26. Pins or the like 27 secured to the wall of the receptacle 16 extend through the slots 26 and limit the tilting movement of the plate 25. The plate 25 is provided at its ends with lugs 28 in which are mounted bolts 29. One of the bolts 29 is designed to engage the rod 23. 100

On the other bolt 29 is mounted a spring 30 adapted to engage the tube 21. It will be 105 seen that the tilting movement of the rod 23

and tube 21 and of the receptacle 22 is limited by the pins 27 in the slots 26 of the plate 25.

The receptacle 22 has in its upper portion an air vent 31 formed around which is a valve seat 32.

Extending upwardly from the top of the receptacle 22 is a bracket 33. Centrally pivoted to the upper portion of the bracket 33 is a bell crank 34. One arm of the bell crank 34 carries the downwardly extending stem 35 of a valve 36 adapted to coact with the seat 32.

On the stem 35 is a spring 36 adapted to engage the top of the receptacle 22, and one arm of the bell crank 34, as shown in Fig. 4, for normally holding the valve 36 away from the seat 32.

Suitably pivoted at one end is a rod 37 having one end secured to the other arm of the bell crank 34 as at 38.

It will be seen that the parts are so arranged that when the receptacle 22 is in its raised position, as illustrated for instance in Figs. 1 and 4, the valve 36 will be held open when the rod 37 is in horizontal position.

When the receptacle 22 is lowered, the bell crank 34 will be moved on its pivot for closing the valve 36. In other words when the receptacle 22 is raised the spring 36^a will hold the valve 36 open. When, however, the receptacle 22 swings downwardly toward its lowered position the pivot point 33^a of the bell crank 34 will be moved away from the point where the rod 37 is pivoted on the receptacle 16 and will thus cause the lower arm of the bell crank to be swung downwardly with relation to the receptacle 22 for seating the valve 36. Secured to the receptacle 22 are chains 39 and 40. The chain 39 is connected with a draft door 12 and the chain 40 is extended over guides 41 and connected with the check door 13, so that when the receptacle 22 is raised the check door is closed and the draft door 12 is opened, whereas when the receptacle 22 is lowered, the door 12 is closed and the door 13 is opened.

In the practical operation of the parts of the device just described, it will be seen that steam from the boiler may enter the receptacle 15 through the pipe 16^a, and that water will collect in the receptacle 15 and will also flow into the receptacle 16.

Mounted in the top of the receptacle 16 is a plug 42 having extended through it an opening 41^a formed at the lower end of which is a valve seat 43. When the pressure in the boiler reaches a certain height, the water in the receptacle 16 will be forced through the tubes 20 and 21 into the tiltable receptacle 22, which will be lowered thereby shutting off the draft door 12 of the furnace and opening the check door 13.

When the pressure in the boiler goes down, the water will flow from the receptacle 22 back into the receptacle 16 and will return to the boiler by means of the bypass tube 44.

It will be seen that when the receptacle 22 is lowered, the air vent therein will be closed thereby preventing any further flow of water into the boiler room.

Mounted just rearwardly of the receptacle 16 is a receptacle 45 which may be tubular. Communicating with the bottom of the receptacle 45 is a return pipe 46 leading to the boiler.

Communicating with the upper portion 80 of the receptacle 45 is a pipe 47 which is the return pipe from the radiators or other parts of the heating system.

A tube 48 located above the level of the tube 47 connects the interiors of the receptacles 16 and 45.

The plug 42 has a hollow cylindrical extension 49 extending downwardly below the seat 43. Screwed into the extension 49 is a collar 50 in which is slidably mounted the stem 51 of a valve 52 designed to coact with the valve seat 43. On the lower end of the stem 51 is a collar 53. Between the collar 53 and the collar 50 may be a spring 54 which normally holds the valve 52 unseated. The cylindrical extension 49 has passages 55, whereby the passage 41^a through the plug 42 is in communication with the interior of the upper portion of the receptacle 16.

On the inner end of the tube 20 is a cam 56, shown in Fig. 3, so arranged that ordinarily it does not contact with the lower end of the stem 51, but when the receptacle 22 is in its lowered position, the tube 20 is rotated to cause the cam 56 to engage the lower end of the stem 51 for seating the valve 52.

Ordinarily return water from the radiators passes from the tube 47 into the receptacle 45 and thence through the tube 46 to the boiler. In case of any small collection of water in the receptacle 45 air may pass from the receptacle through the tube 48, the passages 55 and the passage 41^a so that the system cannot be air clogged. If it should occur, however, that for any reason the return flow to the boiler should be stopped, and this sometimes occurs in heating systems of this type, it will be seen that the receptacle 45 will fill with water which will flow through the tube 48 into the receptacle 16 and thence through the tubes 20 and 21 into the receptacle 22 which will be lowered thereby shutting off the draft through the furnace and opening the check damper and simultaneously closing the valve 52, and thereby preventing any overflow of the return water.

On the receptacle 15 is a water gage 60.

I believe that I have provided an entirely new attachment for heating systems of this type, wherein the dampers are regulated not only by the pressure in the boiler but also in 5 such a way that the draft will be reduced in case the return flow from the radiators should be stopped for any reason.

Furthermore my device has the advantage 10 of automatically preventing leakage from the receptacle 22 and any leakage from the return system.

I, of course, have not attempted to 15 enumerate all the advantages of my improved damper regulator, and I realize that some changes may be made in the construction and arrangement of the parts thereof without departing from the essential features and purposes of my invention, and it 20 is my intention to cover by my claims any modified forms of structure or use of mechanical equivalents which may be reasonably included within the scope of my claims.

I claim as my invention:

1. In a device of the class described, a pair 25 of compartments, the lower ends of said compartments being in communication with each other, means for connecting the upper portion of one of said compartments with the upper part of a boiler, a tube pivotally mounted on the wall of the other of said compartments at the upper portion thereof, and communicating with the interior of said other compartment, a receptacle on the free 30 end of said tube communicating therewith, a counterbalance device for said tube and said

receptacle, a return fluid receptacle having an intake opening near its upper end, and a discharge opening at its lower end, the upper portion of said second receptacle being in communication with the compartment which 40 communicates directly with said pivoted tube, said last named compartment having an air vent, a valve seat adjacent to said air vent, a valve for coacting with said seat, and means actuated according to the movement of said first receptacle for closing said valve. 45

2. In a device of the class described, a receptacle, a tube pivotally supported thereon and arranged in communication with the interior portion thereof, a second receptacle on said tube designed to be operatively connected with draft operating means of a furnace, a counter-balancing device on said tube, a third receptacle having its upper end 50 designed to be in communication with the return pipes of a vapor heating system, and its lower end in communication with a boiler, the upper ends of said first and third receptacle being in communication with each 55 other, whereby said second receptacle will be lowered in case the free flow of return water through said first receptacle should be obstructed, said first receptacle having an air vent, a valve for controlling said air vent, 60 and means for automatically closing said valve when said second receptacle is in its lowered position. 65

Des Moines, Iowa, October 26, 1917.

THOMAS CONNELL.
